DESIGN FOR A DRESS

George Constantine, New York, N. Y.

Application August 12, 1941, Serial No. 102,793

Term of patent 3½ years

To all whom it may concern:

Be it known that I, George Constantine, a citizen of the United States of America, residing in New York city, county of New York, and state of New York, have invented a new, original, and ornamental Design for a Dress, of which the following is a specification, reference being had to the accompanying drawing, forming part hereof.

Fig. 1 is a front view of a dress showing my new design.

Fig. 2 is a rear view thereof.

The characteristic feature of my design resides in the combination on the belted dress disclosed of the specific embroidery arranged on the blouse front and around the neckline, as shown.

I claim:

The ornamental design for a dress, substantially as shown and described.

GEORGE CONSTANTINE.
